ACTIVITY TOY

Timothy J. McHugh, Eastchester, N.Y., assignor to Kohner Bros., New York, N.Y.

Application March 2, 1959, Serial No. 54,812

Term of patent 14 years

(Cl. D25—1)

The dominant feature of my design resides in the portion shown in full lines.

I claim:

The ornamental design for an activity toy, as shown and described.
